UNITED STATES PATENT OFFICE.

JOHN BOSTON, OF NEWARK, NEW JERSEY, ASSIGNOR, BY MESNE ASSIGNMENTS, TO
THOMAS HARDEN CARTER.

STRIP-FEEDING MECHANISM FOR SEWING MACHINES.

Application filed September 4, 1918. Serial No. 252,527.

To all whom it may concern:

Be it known that I, JOHN BOSTON, a citizen of the United States, and a resident of Newark, in the county of Essex and State 5 of New Jersey, have invented certain and useful Improvements in Strip-Feeding Mechanism for Sewing Machines, of which the following is a specification.

My invention relates to mechanisms for 10 use on sewing machines generally but I have applied the same to hemstitching machines such as are used for hemstitching the side edges of long strips of fabric which are to be cut into short lengths and hemstitched 15 across the ends to form handkerchiefs, and I will describe my invention as applied to such machines without intending to limit it to such application.

My invention relates more particularly 20 to the application to a sewing machine of the above general type of a feeding means for conveying the strip to be stitched to the machine and subsequently rolling the strip.

The object of my invention is to provide 25 mechanism which may be applied to hemstitching or sewing machines for the purpose of rendering them as nearly as possible automatic in their operation. The advantage of this is, that a single operator, with- 30 out special training, may attend to a number of machines.

The invention includes mechanism for winding or reeling up the strip of fabric as 35 it is being stitched, and this is adapted to retain the fabric smooth while it is being stitched and to wind it under desired tension. This branch of the mechanism is also adapted to permit the operator to draw back the fabric, as for instance after the 40 sewing thread has been broken, in order to restart the stitching at the point where it may have terminated before the thread had been broken, in order that the stitching on the finished strip may be continuous.

Another object of my invention is to provide 45 mechanism for carrying out the above and which may be attached to the standard machines now on the market and without interfering with their operation and which 50 mechanism shall be simple to manufacture and to operate.

A further object is to provide a simple 55 and practical strip feeding mechanism for sewing machines which may be inexpensively manufactured and assembled and applied to

sewing machines now in general use without material alteration.

Other objects will be in part obvious from the annexed drawings and in part indicated from the following analysis of the invention.

The invention accordingly consists in the features of construction, combination of parts, and in the unique relation of the various members and the relative proportion- 65 ing and dispositioning thereof, all as more clearly outlined herein.

To enable others skilled in the art to fully comprehend the underlying features thereof, in order that they may embody the same, by 70 numerous modifications in structure and relation contemplated by this invention, drawings depicting a preferred form have been annexed as part of this disclosure and in such drawings like characters of reference 75 indicate corresponding parts throughout all the views, of which—

Figure 1 is a front elevation of one of various possible embodiments of the invention, certain parts being broken away or removed 80 for the sake of clearness.

Figure 2 is a rear elevation thereof,

Figure 3 is a plan view with the gate omitted,

Figure 4 is a view showing the lower 85 parts of the machine in end elevation, and it is taken on the line 4—4 of Figure 11.

Figure 5 is a sectional view taken on the line 5—5 of Figure 1,

Figure 6 is a sectional view taken on the 90 line 6—6 of Figure 1,

Figure 7 is a detail of one of the cam motions,

Figure 8 is a face view of part of the head 95 of the machine and showing the thread testing device,

Figure 9 is a sectional view taken on the line 9—9 of Figure 4,

Figure 10 is an enlarged sectional view of the device for controlling the fabric winding 100 device,

Figure 11 is a plan view of the gate and associated parts,

Figure 12 is a front elevation thereof, and

Figure 13 is a detail view of the rear 105 guide roller.

I have shown a sewing machine 1 mounted on a table or bench 2 on which latter there may be a number of machines mounted in a row or rows so that the driving shaft may 110

be common to a number of machines. The particular machine shown herein is a well known type used for hemstitching the edges of a strip of fabric from which handkerchiefs are to be made and I have shown only such parts of the machine as is necessary to an understanding of the present invention. There is shown the frame 3 of the machine, the needle shaft 4 and needle 5, the thread tension device 6, the take up arm 7, the needle oscillator link 8, the balance wheel 9, pulley 10 and the spool holder 11. The needle thread 12 leads from the spool through the guides 13 through the tension device 6 then over a pin 14, thence over a pin 15 carried by a part of the take up which in the present case also forms part of the stop mechanism; and from there the thread passes through the take up arm 7 to the sewing needle.

The sewing machine is operated from the main shaft 16 by the belt 17 which travels over the pulley 18 on this shaft and over the pulley 10 of the sewing machine. There is a worm 19 on the main shaft 16 and this operates through the worm gear 20 to turn the shaft 21 and the latter operates through the mitre gears 22 to turn a counter shaft 23 at a much slower speed than the main shaft 16. There is a belt 24 traveling over the pulley on the counter shaft 23 and over a pulley 24 on a short shaft 26, by means of which, the shaft 26 is operated from the counter shaft.

Tracing the fabric from the source of supply and through the machine, it will be observed that the fabric is carried up from below over the guide or gate 27 shown in Figure 4. The particular gate shown herein forms the subject matter of my prior Patent No. 1,391,876, which forms no part of the present invention except in so far as it enters into certain combinations herein-after set forth and to which patent cross reference may be had for a more detailed description of its construction. It is to be understood that the particular gate shown herein is not necessary to the use of my present invention as any other form may be used. The fabric passes over a rod 28 carried on the arm 29, thence in front of a rod 30 and over a rod 31, through the lateral guides 32, 33 Figure 11 and thence over the bench 2. While passing over the bench one edge of the fabric passes through a folder 34 which turns the edge, while the needle 5 at the same side stitches it. From the folder the fabric travels to the rear of the bench and there it passes over a roller 35 Figure 10 against which it is lightly pressed by idlers 36 carried on a vertically movable shaft 37 journaled in brackets 38. If the fabric is being run through for the first time, i. e. if the first edge is being stitched, then it may be allowed to fall from the roller 35 into a pile or into a receptacle placed below the roller. But if it is being stitched for the second time, i. e., if one edge has been previously stitched and it is being run through for the stitching of the second edge, then the forward end is directed from the roller 35 onto the take up or reeling roller 38 Figure 1 below the table. This roller is operated from the short shaft 26 by a crank pin 39 Figure 9 which projects into one end of the roller and which serves to turn the roller in order to wind the fabric upon it. The shaft 26 has a loose pulley 40 and when the belt 24 is engaging this pulley the shaft 26 remains idle. There is a pulley 25 next to the idle pulley 40 and this frictionally drives the shaft 26 through a disk 41 fixed to the shaft and against which the pulley 25 is pressed by a spring 42 the tension of which may be altered by adjusting the nut 43. When the belt 24 is slipped to the pulley 25 the shaft is operated, but there may be a slippage as between the pulley 25 and the disk 41 so that the shaft 26 and therefore the roller are not always turning at the same speed as the pulley 25. Near the upper roller 35 Figure 10 there is a rod 44 carried by arms 45 pivoted on the axis of the roller 35, the arms 45 having weighted extensions 46 to cause the rod 44 to move downwardly. The fabric passes under the rod 44 so that the latter rests down on the fabric and the position of this rod and its carrying arms will depend upon the tautness of the fabric.

There is a link 46^a connected with one of the arms 45 and at its lower end it is fulcrumed to a brake lever 47 which is pivoted at 48 Figure 4. This brake lever has a shoe 49 which engages the reeling up roller 38 so that it may either resist its rotation or permit it to turn freely under the action of its drive. The pulley 25 will ordinarily be operated faster than is required to drive the roller 38 or as fast as the maximum operation of the roller may require and if the operation of the roller is resisted there will be a slippage as between the pulley 25 and disk 41 so that the roller will operate at some speed less than its drive. The object is to drive the roller 38 at all times so that the fabric will be wound up as fast as it is stitched but so that there shall be no great pull on the fabric. The diameter of the fabric on the roller 38 increases as it is wound thereon. In the present arrangement so long as the brake 49 is not pressing on the roller 38 the latter will be operated fast enough to take up the fabric as fast as it is stitched. If the peripheral speed of the roller 38 (and the fabric wound on it) draws tightly on the fabric the latter is drawn taut and it acts on the rod 44 to lift the arms 45. This pulls up the link 46^a and the brake shoe 49 is pressed against the roller 38 the pres-

sure depending upon the degree of tautness of the fabric. The brake shoe will retard the roller 38 so that the disk 41 slips in relation to the pulley 25. The speed of the roller 38 is thus decreased automatically but the sewing machine continues as before. If at any time the roller 38 should not take up the fabric as fast as it is stitched the fabric will become slack, allowing the rod 44 to move down and this will release the pressure of the brake shoe on the roller 38. The latter will then operate faster and take up the slack in the fabric. There is thus an automatic regulation of the reeling up device.

16 The pulley 25 Figure 1 has a second groove 50 and a belt 51 engaging in this groove operates on a pulley 52 to drive the roller 35 over which the fabric passes before it is wound on the take up roller 38.

20 The belt 24 which operates to turn the shaft 26 when engaging the pulley 25 is adapted to be shifted to the loose pulley 40 whenever the shaft 26 is to be thrown out of operation and this is done through a shifting lever 53 pivoted at 54 and operated through a link 55. The link 55 is fulcrumed above to one arm of a bell crank lever 56 Figure 6 which rocks on a pin 57 near the bench 2. To the other arm of this bell crank lever 25 there is fulcrumed a link 58 which has its other end fulcrumed to an arm 59 fixed on a short shaft 60 journaled in the bracket 61 at the rear of the machine frame. There is another arm 62 fixed to this shaft 60 and 30 the link 63 fulcrumed to this arm and extending forward has its other end fulcrumed to the starting lever 64. The latter is fulcrumed at 65 in front of the machine and at its upper end it is provided with an operating handle 66. This controlling or setting lever 64 is adapted to set the whole mechanism into condition for operation and to start the machine, as will be apparent in the subsequent description, and when it is pulled 40 forward for this purpose the shaft 60 is rocked so that the arm 59 operates through the link 58 to rock the bell crank lever 56. This, in turn, pulls up on the link 55, rocks the lever 53 and shifts the belt 24 from the 45 loose pulley 40 to the clutch pulley 25 and the roller 38 is then in operation. If the setting lever is released, so that it moves back to the position shown in Figure 6 the above operations are reversed and the belt 50 55 24 is shifted to the loose pulley 40 so that the roller 38 is thrown out of operation. When this condition exists the operator may draw back the fabric through the folder 34 in order to start the stitching operation on 60 the fabric where the last stitch was made previous to the stopping of the machine. The roller 38 being then not driven, may be reversed when the fabric is pulled back.

65 The hand or setting lever 64 above referred to, operates to throw in or out the clutch of the machine to set the latter into or out of operation. The cam lever 68 rocking on the fulcrum 69 has a cam 70 which is adapted to press the ordinary clutch 71 of the sewing machine so that the pulley 10 70 will operate the machine. The other arm 72 of this cam lever has a pin 73, on which the spring 74 acts to rock the cam lever 68 and thus release the clutch 71 of the machine. The pin 73 is engaged by an arm 75 fixed to the shaft 60 which latter, as above stated, is rocked by the setting lever 64. When the shaft 60 is rocked by the forward movement of the setting lever 64, the arm 75 acting on the pin 73 moves the cam lever 80 68 to throw in the clutch 71. Whenever the setting lever 64 is released it is thrown back by the action of the spring 74 which operates the cam lever 68.

When the fabric is threaded into the machine for the stitching of the first edge it will usually be allowed to fall from the roller 38 without being wound upon this roller as it must be returned to the front of the machine to be fed through again for 85 the stitching of the opposite edge. When the latter is being stitched the fabric may be automatically wound up on the roller 38 and then the latter may be removed, with the fabric on it, and thus conveyed to operators who perform other operations on the fabric. When one roller is removed another and empty roller may be substituted in its place. The fabric after leaving the automatic machine is thus easily handled. 90

The present machine is substantially automatic in its operation. Once the fabric has been started through the machine and the needle threaded, the operator merely pulls forward the setting lever 64 until it is 95 engaged and held by the latch 93. This sets the sewing machine into operation and it sets the automatic winding device into condition for operation. If the fabric is being wound up on the roller 38 it is wound at 100 substantially uniform tension and this tension may be regulated by adjusting the nut 43 so that the pressure of the spring 42 will cause the pulley 25 to clutch the disk 41 with 105 more or less friction. When the fabric is 110 drawn too rapidly by the roller 38 the latter is regulated automatically so that the fabric is wound up as fast as it is stitched but it is not pulled with too great force by the reeling roller. 115

It will thus be seen that the present invention provides a simple and practical apparatus of the above general character well adapted to accomplish among others all of the objects hereinafter set forth. 120

Without further analysis, the foregoing will so fully reveal the gist of the invention that others can, by applying current knowledge, readily adapt it for various applications without omitting certain features that, 125 130

from the standpoint of the prior art, fairly constitute essential characteristics of the generic or specific aspects of this invention, and, therefore, such adaptations should and 5 are intended to be comprehended within the meaning and range of equivalency of the following claims.

I claim:

1. The combination of a sewing machine 10 adapted to stitch a strip of fabric and means for winding up the strip of fabric, including a roller, a slip clutch for operating said roller and a brake controlled by the strip of fabric for resisting the operation of said roller by its operating means 15 to change the speed of operation of the roller for the purpose set forth.
2. The combination of a sewing machine 20 adapted to stitch a strip of fabric and means for winding up the strip of fabric, including a roller, driving means for said roller, a slip clutch device interposed between said driving means and said roller and a brake controlled by the strip of fabric 25 for resisting the operation of said roller to modify the speed of operation of said roller for the purpose set forth.
3. The combination of a sewing machine 30 adapted to stitch a strip of fabric, and means for winding up the strip of fabric, including a roller, a slip clutch for operating said roller, a brake for retarding the operation of the roller and means controlled by the strip of fabric for controlling the operation of said brake, for the purpose set forth.
4. The combination of a sewing machine 35 adapted to stitch a strip of fabric and means for winding up the strip of fabric, including a roller, a slip clutch for operating said roller, a brake for frictionally resisting the operating of said roller by its operating means and means resting against the strip of fabric and adapted to control the operation of said brake for the purpose 45 set forth.
5. The combination of a sewing machine 50 adapted to stitch a strip of fabric, means for winding up the strip of fabric, including a roller, resistable means for operating said roller, means for resisting the operation of said roller by its operating means, a guide roller for the strip of fabric 55 interposed between the stitching mechanism and the winding up means, and means resting on the fabric between the stitching mechanism and said guide roller and adapted to control said resisting means.
6. The combination of a sewing machine 60 adapted to stitch a strip of fabric and means for winding up the strip of fabric, including a roller, a slip clutch for operating said roller, means for adjusting the slip clutch to modify its operating force on said roller and a brake controlled by the 65 strip of fabric for resisting the operation of

said roller by its operating means for the purpose set forth.

7. The combination of a sewing machine adapted to stitch a strip of fabric and means for winding up the strip of fabric, including a roller, driving means for said roller, a clutch device interposed between said driving means and said roller, a spring device for adjusting the clutch device and means controlled by the strip of fabric for 70 resisting the operation of the roller to modify the speed of operation thereof for the purpose set forth.

8. The combination of a sewing machine adapted to stitch a strip of fabric and 75 means for winding up the strip of fabric, including a roller, driving means for said roller, means controlled by the strip of fabric for modifying the action of the driving means on said roller and means for stopping the sewing machine and adapted to release said roller driving means to permit the strip of fabric to be drawn backwards.

9. The combination of a sewing machine adapted to stitch a strip of fabric, means 80 for winding up the strip of fabric, including a roller, driving means for said roller including a belt and a fast pulley for operating the roller, a loose pulley to which said belt is adapted to be shifted, means controlled by the strip of fabric for modifying the action of said driving means on the roller, a starting and stopping device for the sewing machine and a belt shifter adapted to ship said belt to said loose pulley 85 when the machine is stopped and to reshift it to said fast pulley when the sewing machine is started.

10. The combination with a sewing machine, of a starting and stopping lever and a latch for holding the same, a winding up roller and means for operating it to wind up the strip of fabric stitched by the machine, said winding up roller being adapted to be placed into and out of operation by 90 said starting and stopping lever, a device engaging with and controlled by the strip of fabric and adapted to operate said latch and a device engaging with and controlled by the sewing thread and adapted to operate 95 said latch.

11. In combination with an automatic sewing machine of the character set forth, roller means for delivering a strip of fabric to the sewing machine prior to its being stitched, and means for winding the strip of fabric after being stitched, comprising a roller, means frictionally associated therewith for driving said roller, and means controlled by the tension of the fabric after 100 being stitched for increasing and decreasing the rate of rotation of the roller upon which the fabric is being wound to maintain the fabric at substantially uniform tension.

12. In combination with an automatic 105

- sewing machine of the character set forth, roller means for delivering a strip of fabric to the sewing machine prior to its being stitched, and means for winding the strip of fabric after being stitched, comprising a roller, means frictionally associated therewith for driving said roller, and means controlled by the tension of the fabric after being stitched for varying the rate of rotation of the roller upon which the fabric is being wound, said last means including a brake actuated by an increase in tension on the fabric.
13. In combination, with an automatic sewing machine of the character set forth, roller means for feeding a strip of fabric to the machine to be stitched, and roller means for winding the strip of fabric after the same has been stitched, said latter means including a roller, a driving element frictionally connected therewith and means controlled by the tension of the fabric after being stitched for increasing and decreasing the relative rate of movement of the winding roller with respect to the driving element therefor, whereby an increase in tension on the fabric will cause a decrease in the relative rotation of the winding roller and vice versa.
14. In combination, with an automatic sewing machine of the character set forth, roller means for feeding a strip of fabric to the machine to be stitched, and roller means for winding the strip of fabric after the same has been stitched, said latter means including a roller, a driving element frictionally connected therewith, and means controlled by the tension of the fabric after being stitched for increasing and decreasing the relative rate of movement of the winding roller with respect to the driving element therefor, whereby an increase in tension on the fabric will cause a decrease in the relative rotation of the winding roller and vice versa, and means associated with said first roller means for stopping the machine if the supply of fabric fails.
15. In combination, with an automatic sewing machine of the character set forth, a movable gate at the front of the machine over which a strip of fabric is adapted to be guided to the stitching means, and a winding means at the opposite side of the machine upon which the stitched fabric is adapted to be wound, said winding means including a roller and operating means, a slip clutch for operating said roller, and a brake controlled by the strip of fabric for resisting the operation of said roller by its operating means to change the speed of peripheral rotation of said roller.
16. In combination with an automatic sewing machine of the character set forth, a movable gate at the front of the machine over which a strip of fabric is adapted to be guided to the stitching means, and a winding means at the opposite side of the machine upon which the stitched fabric is adapted to be wound, said winding means including a roller and operating means, a slip clutch for operating said roller and a brake controlled by the strip of fabric for resisting the operation of said roller by its operating means to change the speed of peripheral rotation of said roller, and means associated with said gate for disconnecting said roller from its operating means if the supply of fabric fails.
17. In combination with an automatic sewing machine of the character set forth, a movable gate at one side of the machine, roller means for guiding a strip of fabric thereover to the machine to be stitched, roller means at the opposite side of the machine upon which the stitched strip is adapted to be wound, said roller means including a loosely mounted roller, a frictional drive for said roller including a fast and loose pulley, a belt shifter, means for varying the peripheral speed of the winding roller in accordance with the tension exerted upon the stitched strip of fabric, and means actuated from the gate for shifting a driving belt from the fast to the loose pulley.
18. In combination with an automatic sewing machine of the character set forth, a movable gate at one side of the machine, roller means for guiding a strip of fabric thereover to the machine to be stitched, roller means at the opposite side of the machine upon which the stitched strip is adapted to be wound, said roller means including a loosely mounted roller, a frictional drive for said roller including a fast and loose pulley, a belt shifter, means for varying the peripheral speed of the winding roller in accordance with the tension exerted upon the stitched strip of fabric, and connections between the gate and the belt shifter whereby the belt may be shifted automatically under certain predetermined conditions of the gate.

Signed at the city of Newark, county of Essex, and State of New Jersey this 24th day of July, 1918.

JOHN BOSTON.
